UNITED STATES PATENT OFFICE.

WILLIAM E. PINCKNEY, OF PORTLAND, OREGON, ASSIGNOR TO COLUMBIA WASHING MACHINE MANUFACTURING COMPANY, OF PORTLAND, OREGON.

OPERATING MECHANISM FOR WASHING MACHINES.

Application filed September 24, 1924. Serial No. 739,604.

To all whom it may concern:

Be it hereby known that I, WILLIAM E. PINCKNEY, a citizen of the United States, and a resident of Portland, in the county 5 of Multnomah and State of Oregon, have invented a new and useful Operating Mechanism for Washing Machines, of which the following is a specification.

This invention relates generally to the 10 washing machine industry and more particularly to operating machines for driving the wringer mechanism of a washing machine, by means of a mechanism especially adapted to be operated from the main drive 15 shaft, so that, by a simple interchange of a single pair of gears, the speed of the wringer shaft can be changed from 48 R. P. M. to 715 R. P. M.

I accomplish these results in the manner 20 set forth in the following specification and illustrated in the accompanying drawing, in which:

Figure 1 is a section taken along the line 1—1 in Fig. 3.

Figure 2 is a section taken along the line 25 2—2 in Fig. 1.

Figure 3 is a section taken along the line 3—3 in Fig. 1.

Figure 4 is a section taken along the line 30 4—4 in Fig. 1.

Attention is drawn to my Patent No. 1,492,808, over which this is an improvement, and in this application, only those parts are illustrated which actually form a 35 part of the invention.

Similar numbers of reference refer to the same or similar parts throughout the several views.

Referring in detail to the drawing, I have 40 illustrated a gear case 10, which is attached to the side of the washing machine (not shown), as is the case in the above mentioned patent. The cylinder drive shaft 11, pinion 12, clutch 13, and operating lever 14, as well 45 as the segment gear 15, and connecting rod 16, are the same as in the patent above referred to.

On the back 17, of the case 10, I have mounted a spur crank gear 18, to which the 50 rod 16, is connected by means of the pin 19.

On the back 17, I have formed an offset whose rear wall 20, supports a drive shaft 21, through which power is supplied to the device. Shaft 21, journals at its forward 55 end in the bearing 22, in the flange 23.

A bearing 24, on the wall 20, and a bearing 25, formed on the flange 23, carry the transverse counter shaft 26, which is held in position by the screw plugs 27. Pinned on the shaft 26, and meshing with the gear 18, 60 is a pinion 28.

I have placed a standard 29, on the inside of the back 20, which standard supports a bearing 30. The shaft 31, journals in the bearing 30 and the bearing 32, on the side 33, 65 of the gear box 10. On one side of the shaft 31, I have pinned a miter gear 34, which meshes with the miter gear 35, on the shaft 26.

On the shaft 31 is secured a worm wheel 70 36, which is driven by a worm 37, on the drive shaft 21. On the drive shaft 21, is also secured a spiral pinion 38, which meshes with the spiral gear 39, on the vertical wringer drive shaft 40, which journals in 75 the bearings 41 and 42, on the upper and lower sides of the gear box 10. A cover 43, is placed across the front of the gear box 10, to keep out the dust and to confine 80 a lubricant.

By this arrangement, a relatively high motor speed applied to the shaft 21, may be branched out to a moderately high speed 715 R. P. M. which is suitable for a centrifugal wringer on the one side and to supply 85 the correct speed for the cylinder operating mechanism on the other. By the simple substitution of the spiral gear 39, with a worm wheel, the speed of a shaft 40 may be easily dropped to 48 or 50 R. P. M. which is 90 about the correct speed for the roll wringer shafts.

This makes the device especially adaptable for the manufacturer who produces washing machines of both the roll and centrifugal types of wringers.

I am aware that washing machine operating devices, have been constructed in the past in great numbers.

I therefore do not claim such devices 100 broadly, but I do intend to cover all such forms and modifications of same, as fall fairly within the appended claim.

I claim:

An operating mechanism for washing machines, having in combination a flat vertical gear box; a horizontal drive shaft passing transversely through the back of said box; a worm on said drive shaft; a horizontal longitudinal shaft over said worm at right 105 110

angles to said drive shaft; a worm wheel on said longitudinal shaft meshing with said worm; a transverse counter shaft in the same plane as is said longitudinal shaft; miter gears connecting said counter shaft and longitudinal shaft; a spiral pinion on said drive shaft; a vertical wringer drive shaft; a spiral gear on said wringer drive shaft meshing with said spiral pinion; a spur pinion

on said counter shaft; a spur crank gear 10 mounted in said gear case and meshing with said spur gear; a segment gear in said case rocked by said crank and a cylinder actuating shaft projecting through said gear case having a pinion thereon, meshing with said 15 segment gear.

WILLIAM E. PINCKNEY.
